UNITED STATES PATENT OFFICE.

GEORGE F. VOIGHT, OF OAKLAND, CALIFORNIA, ASSIGNOR TO ECONOMY PRODUCTS CORPORATION, A CORPORATION OF CALIFORNIA.

WIRE LATH.

Application filed June 15, 1926. Serial No. 116,131.

My invention relates to improvements in wire lath adapted for reinforcing the stucco composition of stucco structures, although also useful for other purposes; and one of 5 the objects thereof is to provide wire lath having off-sets formed therein at intervals adapted to seat against the stucco backing, whereby the body portion of the lath will be maintained in spaced relation to the back- 10 ing; a further object is to provide sheet metal fastening clips having opposed ends looped around spaced inter-twisted portions of the off-sets and permanently attached thereto by means of a metallic filler dis- 15 posed in the interstices within said looped ends, said filler comprising preferably zinc or a composition of metal comprising a major portion of zinc and applied while in a hot fluid state, said slips having an inter- 20 mediate portion perforated for the reception of a nail or other fastening device adapted to be driven in the stucco backing for attaching the lath thereagainst; a still further object is to so arrange the fastening clip that 25 its intermediate portion will normally be spaced a distance from the face of the stucco backing when the lath is initially disposed thereagainst preparatory to attaching it thereto, whereby the securing nail may be 30 employed in the manner of a lever for drawing the lath taut prior to driving the nail home into the backing.

With the foregoing and still further objects and purposes in view which will appear as the description proceeds, my invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawings—

Figure 1 is a face view of wire lath constructed in accordance with the present invention, attached to the stucco backing of a stucco structure;

Figure 2 is a face view of a portion of the lath attached to the stucco backing;

Figure 3 is a sectional view on line 3'-3' of Fig. 2;

Figure 4 is a sectional view on line 4'-4' of Fig. 2;

Figure 5 is a side elevation of a fragment

of the stucco backing, an edge view of the fastening clip disposed thereagainst, and a view of the securing nail in position for stretching the lath; and

Figure 6 is a cross sectional view of one of 60 the looped ends of the clip and an inter-twisted portion of the lath.

Referring to drawings in detail, throughout which like reference characters designate like parts:

The numeral 1 designates the customary sheathing boards secured across the face of the studding and other frame timbers constituting the frame-work of a stucco structure. Across the face of the sheathing 70 boards 1 is preferably disposed a course of building paper 1', the latter adapted as a waterproofing media for preventing water from penetrating from the stucco coating to the wood-work of the structure. 75

The sheathing boards 1 and building paper 1' will hereinafter be referred to as a single unit and designated "backing" or "stucco backing".

3 designates my improved wire lath, 80 which embodies a plurality of wires 4 inter-twisted at short intervals thereby forming diamond-shaped meshes having opposed inter-twisted portion 5. The body of the lath is provided at intervals with shallow 85 cup-shaped off-sets 6, which are formed by pressing portions of the wires to one side out of the plane of said body.

The apexes or heads of the off-sets 6 are circumscribed by the dotted lines 7, and the 90 inclining side walls thereof are defined as lying between said lines 7 and the dotted lines 8.

The apexes of the off-sets include each preferably one complete mesh of the lath, 95 whereby a laterally opposed pair of the inter-twisted portions 5 will be disposed in a plane substantially parallel with the body of the lath.

9 designates the fastening clips, which 100 comprise an oblong strip of sheet metal disposed to extend across the short diameter of the mesh at the apex of the off-set, and with its ends formed into loops embracing the two opposed inter-twisted portions thereof, and is provided intermediate its ends with a perforation 10, through which is projected a nail 11 adapted to be driven in the backing 1, 1' for securing the lath thereagainst. 105

The clip 9 is preferably formed, and arranged relative to the off-set, so that its intermediate portion will be spaced a short distance from the face of the backing 1, 1', when its looped ends are disposed in contact therewith, thereby permitting the nail 11 when it is projected through the opening 10 to be used as a lever for drawing the lath taut before securing it to the backing, 10 by inclining its upper end in a direction opposite to that in which it is desired to draw the lath (see Fig. 5), in which inclined position it is given a light tap with the hammer to enter its point a short distance in the 15 face of the backing for fulcruming it thereagainst, then by moving its upper end in the direction the lath is to be drawn it will force the latter to be drawn over in the same direction, after which the nail is driven home 20 into the backing until its head engages and binds the clip 9 thereagainst. In case it is found unnecessary to stretch the lath before securing it to the backing, the nail 11 is simply projected through the perforation 10 and driven into said backing until the head engages and binds the clip 9 thereagainst, 25 as hereinbefore described. (See Fig. 3.)

The sheet metal of which the clips 9 are constructed is intended to be sufficiently 30 pliant to permit the intermediate portion of the clip to bend when engaged by the head of the nail when the latter is driven a proper distance in the backing, to permit it to engage the latter between said inter-twisted portions.

The ends of the clips 9, after the same have been looped around the inter-twisted portions 5, are preferably fixedly bound thereto by interposing a metallic binder or 40 filler 12 in the intertices inside the loops between portions of the latter and said inter-twisted portions 5, said binder or filler 12 comprising preferably zinc or a metallic composite composed partly of zinc, and applied while in a hot fluid state, by immersing the lath with the clips attached thereto in said fluid. Such immersion of the lath and clips in said fluid, obviously, will cause

a metallic film or coating to form on the exterior thereof and to extend thereacross at 50 their points of union or intersection, thereby further fixedly and rigidly securing said clips and lath together.

After securing the lath to the stucco backing by means of the securing nails 11, the 55 stucco composition 13 is preferably applied by spreading it on the backing 1, 1' and on and around the lath until a stucco coating of suitable thickness is obtained.

It is to be understood that I do not desire 60 to confine the use of the present improved wire lath to its application to the particular stucco backing hereinabove described, but instead the same may be used in conjunction with any other kind or form of backing 65 suitable to receive the stucco composition. It is further to be understood that the off-sets 6 may be modified in form to best conform with the work for which the lath is to be used.

70 I claim:

1. Wire lath having a lateral off-set portion in the body thereof, said offset portion having an apex embodying a pair of laterally spaced intertwisted wires, a sheet 75 metal fastening clip having opposed ends attached to said wires, said clip having an intermediate part normally disposed in a plane lying out of the body of the lath, said part having an opening adapted to receive a 80 securing nail, said nail adapted to be driven in a support for engaging said part for bending it for binding it against said support between said wires.

2. Wire lath having a lateral off-set portion in the body thereof, a strip of sheet metal with its ends formed into loops embracing spaced parts of said off-set portion, said strip arranged relatively to the off-set portion so that its intermediate portion will be spaced from the face of a backing 90 when its looped ends are disposed in contact therewith, said strip having a perforation adapted to receive a nail.

85 GEORGE F. VOIGHT.
